UNITED STATES PATENT OFFICE

91,145

DESIGN FOR A BUILDING STRUCTURE

William C. Scherer, Detroit, Mich.

Application August 5, 1933. Serial No. 48,926

Term of patent 7 years

To all whom it may concern:

Be it known that I, WILLIAM C. SCHERER, a citizen of the United States, residing at Detroit, county of Wayne, State of Michigan, have invented a new, original, and ornamental Design for a Building Structure, of which the following is a specification, reference being had to the accompanying drawing forming part thereof.

Fig. 1 is a front perspective view of my building structure,

Fig. 2 is a front elevation thereof,

Fig. 3 is an end elevation thereof.

Conventional lettering is supported above the electric light hood cornice "10". The diagonal shaded bands of the drawing are intended to represent contrasting color.

I claim:

The ornamental design for a building structure as shown and described.

WILLIAM C. SCHERER.
